BESSIE LAZELL BROWN, OF SHEEPSHEAD BAY, NEW YORK.

GIRL'S UNDERWAIST.

1,324,639.

Specification of Letters Patent. Patented Dec. 9, 1919.

Application filed November 6, 1918. Serial No. 261,317.

To all whom it may concern:

Be it known that I, BESSIE LAZELL BROWN, of Sheepshead Bay, in the county of Kings and State of New York, have invented certain new and useful Improvements in Girls' Underwaists; and I do hereby declare the following to be a full, clear, and exact description of the invention, such as will enable others skilled in the art to which it app pertains to make and use the same.

My invention is illustrated in the accompanying drawings where Figure 1 shows a front view of the garment in use and Figs. 2 and 3 side and rear elevations, respectively.

The garment, made of muslin, percale or the like, is shown consisting of a single piece of material 1 which may fasten at the front or back, and, if desired two rows of buttons or other securing devices may be used to allow of adjustment.

The shoulder straps 2 form, with the body portion, the arm sizes 3. They are shown attached to each of the meeting edges of the garment at the top of the back as in Fig. 3, 25 and extending over the base or nape of the neck, that is the stationary part of the clavicle, and straight down to the upper edge of the front as in Fig. 1. This so locates the straps that they naturally tend to remain in contact with the nape of the neck and out 30 of contact with the movable part of the clavicle or collar bone. The straps are preferably provided with two or more fastening devices 4 shown attached over the shoulder.

The garment substantially incloses the waist and upper body of the wearer to constitute a bust and abdominal support and its main portion at the front terminates at its lower end above the hips while at the 40 rear it extends downward toward the sides two inches or more farther than the front. The sides are cut away to form recesses 5 which are bridged by elastics 6.

From each side of the front lower edge a 45 broad tapering band 7, whose rear edge is about in line with the front edge of the recess 5, extends downward and rearward over and forms a support for the hip and thigh and is equipped with an elastic hose 50 supporter. A co-acting band 8 extends from each side of the rear lower edge of the garment as at 9, below the recess 5, downward and forward over the thigh and crosses, and is secured to, the band 7 as at 10. It, also, 55 is provided with an elastic hose supporter. The waist is shown equipped with buttons

12 to which nether garments, skirts, etc., may be attached.

There are certain well settled orthopaedic principles recognized by those familiar with this art to whom the advantages of my invention will readily appeal. One of these is that the main tendency to slip-shod carriage and appearance in growing girls is due to garments which allow the weight of the 60 clothing and the pull upon the hose supporters to cause pressure on the outer tips of the shoulders, that is the movable parts of the clavicle or collar bone. This tends to drag the shoulders forward and depress the 65 chest. It is generally recognized that the proper point of location for the weight and pull is on the stationary part of the clavicle near the base or nape of the neck at the sides and back. Manifestly my garment, known 70 commercially as "junior waist", meets this requirement. It is equally apparent that in a garment whose shoulder straps extend up from the waist line and cross in the back, the 75 straps, even though they normally lie close to the neck, must pull and cause friction as the girl performs athletic exercise. I avoid this entirely and at the same time insure holding the back straight and erect and the shoulders flat on the back.

Another important principle is that the bust and abdomen should be supported but not by the movable parts sustaining the 80 weight and strain. Reference to Fig. 1 will show that while the garment provides adequate bust and abdominal support yet there 85 is no pull or variation of pressure or friction at those points.

A third principle is that a substantial connection must exist between the garment 90 proper and the stockings but it must not restrict the natural energy or center the strain over the abdomen. My bands 7 and 8 not only meet these requirements by reason of their locations over the thighs and their 95 positions relative to the recesses 5 and the shoulder straps, but they also furnish a substantial support for the body in all positions while allowing the utmost freedom in play or athletic exercise.

I claim as my invention:

1. A girl's underwaist having a body portion constituting a bust and abdominal support and formed with a recess in each of its sides, the garment being equipped with two 100 broad spaced apart bands extending from the sides of the front lower edge of the body

portion downward and rearward beneath said recesses to constitute hose supporters and supports for the hips and thighs.

2. A girl's underwaist opening at the back and having shoulder straps extending from near the meeting edges of the garment and adapted to extend over the base of the neck of the wearer and secured to the upper edge of the front of the garment, said waist constituting a bust and abdominal support and having two broad spaced apart tapering bands extending from each side of the front lower edge of the garment downward and rearward, said garment terminating at the sides of the back lower than in front, a recess being formed in each of its sides, and bands extending downward and forward from the sides of the back and crossing and secured to said former bands, said bands constituting hose supporters.

3. A girl's underwaist having recesses in

its sides and elastics bridging said recesses, broad tapering bands extending downward and rearward from the garment in front of said recesses, and bands extending downward and forward from the garment in rear of said recesses, the respective pairs of bands being crossed and secured together and equipped with hose supporters.

4. A girl's underwaist comprising a body portion terminating above the hips at its front and extending lower at the back, shoulder straps attached to the back near its center, bands extending downward and rearward from the front and bands extending downward and forward from the back, said bands being crossed and secured together and equipped with hose supporters.

In testimony whereof I have signed this specification.

BESSIE LAZELL BROWN.
